SAMUEL BEECHER, OF NEWTON, MASSACHUSETTS

ELECTRICAL CANDLE DISPLAY

Application filed June 30, 1931. Serial No. 547,885.

This invention relates to electrical candle displays or so-called candelabra of the type placed for decorative purposes on window-sills, especially during the Christmas season. 5 These displays usually consist of a base adapted to be supported on the sill and containing a row of upstanding candle-simulating elements terminating in torch-shaped electric bulbs which when illuminated bear a 10 resemblance to lighted candles.

In accordance with the present invention, I provide a unitary display of simple construction which can be accommodated by window-sills of different lengths and widths. 15 I am using the term "length" herein as connoting the long dimension of the sill and corresponding to the width of the window, and the term "width" as defining the short dimension or depth of the sill. In brief, my 20 display is made up of three sections and includes a central section to which is hingedly secured the two end-sections in such a way that the three sections may be kept in tandem or end-to-end relationship as a display 25 of maximum length, or the two end-sections swung away, as desired, from the central section to an extreme position affording a display of minimum length.

With the foregoing and other features and 30 objects in view, I shall now describe my invention in conjunction with the accompanying drawings, wherein

Figure 1 illustrates in perspective a candle display embodying the present invention.

Figure 2 shows the display mounted on a support with the end-sections swung to extreme side-by-side relationship with the central section.

Figure 3 is a plan view of the mounting on 40 the line 3-3 of Figure 2.

Figure 4 represents in plan view another possible mounting of the display on a short and narrow window-sill.

Figure 5 is a section on the line 5-5 of 45 Figure 4.

Referring in detail to the drawings, the base for the display is preferably of rectangular form and is made up of a central section 1 and two end-sections 2, all made of 50 wood or other suitable material and capable

of resting on a window-sill or other flat support. Each end-section is hingedly secured by a suitable hinge member 3 to the central section, with the pintle 4 of the hinge located substantially where a corner edge of the end-section and a corner edge of the central section coincide. This makes it possible for each end-section to occupy two desirable extreme positions, one being in end-to-end relationship, and the other being in side-by-side relationship with the central section. The two end-sections are preferably of equal length and of a combined length preferably not in excess of the length of the central section, whereby they can both be swung simultaneously in side-by-side relationship with the central section to produce a rectangular base of minimum length, as shown in Figure 3. Affixed in upstanding position in the base is a row of tubular elements 5, which may be constructed to simulate candles in a well-known manner. Thus, they may be coated with white enamel or other suitable material and be socketed at their upper ends for the reception of electric bulbs 6, preferably of a torch shape so as to simulate candle flames when illuminated. The bulbs may be connected in series in the usual manner, with the wiring 7 leading to the successive sockets through the tubes and running through a channel or bore 8 formed longitudinally through all the sections of the base, sufficient slack being left in the wiring to permit the end-sections to be swung freely from an extreme tandem arrangement indicated as being possible in Figure 1 to an extreme side-by-side relationship with the central section, best shown in Figure 3. It is preferable that the tubes 5 progressively increase in height from the ends toward the center of the base, for not only does this permit one to secure the pleasing upwardly tapered array of candle-simulating elements shown in Figure 1, but also the even more pleasing and compact double-bank arrangement shown in Figure 2, where the front bank of candle-simulating elements tapers downwardly from its ends and the rear bank tapers upwardly from its ends. The arrangement of Figure 2 may

be employed, especially in the case of short window-sills which cannot accommodate a tandem arrangement of the sections, although it may, of course, also be used in the case of 5 long window-sills. While the display is shown as having eight candle-simulating elements in all, with the end-sections each carrying two elements to produce a symmetrical or balanced effect, it is obvious that a greater or 10 fewer number of elements might be used, if desired.

It is, of course, possible to have a number of other arrangements intermediate a tandem and a side-by-side relationship of the 15 sections. Thus, where a window sill is of insufficient length and width to permit support of the display as shown in Figures 2 and 3, the display may be supported as illustrated in Figures 4 and 5, where the end-sections 2 are turned substantially at right angles to the central section 1 and rest on the sill 9 while the central section is off the sill and so must be independently supported in 20 order to avoid toppling of the display. Such support for the central section may easily be had by a suitable bracket 10 which, as shown, consists of a strip of metal having a horizontal supporting arm 11 for the central section, and which takes a downward turn near the 25 sill edge 12 and terminates under the window-sill, whereat it may be anchored to the sill by suitable fastening means, such as the screws 18.

30 I am aware of the fact that it has been proposed to construct candelabras which can be adjusted to meet the requirements of window frames of different sizes, but the construction of the present invention possesses the merit of simplicity, compactness, and 35 ease of adjustment in meeting various requirements.

I claim:

40 1. A device of the character described, comprising a substantially rectangular base made up of at least three adjacent longitudinal sections, candle-simulating elements fixed in upstanding position in all of said sections, and a pair of hinge members by which said 45 end-sections are secured to the adjacent section, the pintle of each of said hinge members being located substantially at the line of coincidence between a corner edge of each end-section and a corner edge of said adjacent section, whereby said end-sections may be 50 swung away freely from a tandem arrangement of said sections and thus permit said device to be mounted on window-sills of various 55 lengths.

60 2. A device of the character described, comprising a substantially rectangular base made up of three adjacent longitudinal sections, candle-simulating elements terminating in electric bulbs fixed in upstanding position in all of said sections and of progressively increasing height from the ends to the 65

center of said base, and hinge members by which said end-sections are secured to the central section, the pintle of each of said hinge members being located substantially at the line of coincidence between a corner edge of each end-section and a corner edge of said central section, and said end-sections being of substantially equal length and of a combined length not exceeding the length of said central section, whereby said end-sections may be swung away freely from an end-to-end relationship to a side-by-side relationship with the central section.

70 In testimony whereof I have affixed my signature.
